UNITED STATES PATENT OFFICE.

WILLIAM JAMES MYATT, OF BIRMINGHAM, ENGLAND.

BLADE-HOLDER OF SAFETY-RAZORS.

1,087,544.

Specification of Letters Patent. Patented Feb. 17, 1914.

Application filed June 17, 1912. Serial No. 704,002.

To all whom it may concern:

Be it known that I, WILLIAM JAMES MYATT, a subject of His Majesty the King of England, and residing at Birmingham, in England, have invented new and useful Improvements in or Relating to Blade-Holders of Safety-Razors, of which the following is a specification.

This invention comprises certain improvements in or relating to blade holders, for safety razor blades, of the type comprising upper and lower jaws adapted to receive the rear portion of the blade, and it has for its object a holder which better facilitates the positioning and detachable securing of the blade within the holder than heretofore.

To these ends the invention consists in the constructions and combinations of parts such as will be hereinafter described and pointed out in the claims which conclude this description.

In the accompanying drawings: Figures 1 and 2 are respectively side and front elevations of the upper part of a safety razor provided with a blade holder constructed according to the invention. Fig. 3 is a view of a blade holder having a blade secured therein. Fig. 4 is a view of the blade holder illustrated in Fig. 3, showing the blade removed therefrom, and the locking parts out of the "engaging" position. Fig. 5 is a transverse section on line $\alpha\alpha$ of Fig. 3. Fig. 6 is a longitudinal section on line $y\gamma$ of Fig. 3. Fig. 7 is a longitudinal section on line $y'y'$ of Fig. 4. Fig. 8 is a sectional plan, the section being taken on line $z\zeta$ of Fig. 7.

Referring to Figs. 1 to 8 inclusive the holder 1 is formed from sheet metal bent upon itself and around the hinge pin 1^a and a pin 2 is rotatably fitted at each side of the holder, the portion 3 of such pin which extends between the jaws being notched as at 9 to a depth conveniently equal to half the diameter of the pin. One end of the pin 2 is provided with a cup head 4 which abuts against the underside of the lower jaw 5, and at its other end is provided with any suitable means to facilitate the rotation of the pin. Such means may consist of a lever comprising a disk having an outwardly projecting arm 6, and having a rectangular aperture 7 to fit over the corresponding shaped end of the pin 2 which end is then riveted over to hold the disk in

position upon such pin and against the upper jaw 8 of the holder. To fix the blade in position the notched pins 2 are turned by means of the projecting arms 6 so that the notches 9 are disposed on the inside and adjacent one another as shown by Fig. 4 thereby allowing the blade 10 to pass therebetween. The blade is then pushed between the jaws 5 and 8 of the holder whereupon the side notches 11 of the blade register with the notches 9 in the pin, the pins being then rotated through 180° so that the unnotched part of the pin engages in the notches 11 of the blade 10 to thus prevent the removal of the blade. The pins 2 preferably engage with the rear sides of the blade notches 11 to hold the blade against the back of the holder to thereby prevent any looseness of fitting. The thumb lever thus provides very convenient and compact means for rotating the notched pins, as to rotate such pins, the thumb may be merely placed on the lever and pressed downwardly and outwardly. The thumb levers are prevented by their frictional engagement with the surface of the holder from being inadvertently rotated, the inherent resiliency of the folded sheet metal holder or the lever causing such lever and holder to be pressed together. This feature is specially advantageous in the case of a holder retaining the blade while being stropped, as during the stropping the levers are liable to frictionally engage with the strop and be rotated and thus allow the holder to release the blade. This resiliency of the holder also enables the jaws to obtain a better grip upon the blade as when the thumb levers are closed the pressure of the same on the jaws tends to close said jaws upon the blade.

Having thus described my invention what I claim as new and desire to secure by Letters Patent of the United States of America is:—

1. A pivotally mounted blade holder comprising upper and lower jaws between which the blade is placed from the front thereof, and locking and positioning means adapted to engage with side notches in the razor blade, which locking and positioning means comprise a rotatably mounted pin extending between the jaws and adapted to be rotated to be moved out of and into engagement with a side notch in the blade, and thumb operated means attached to said pin which

frictionally engages with the surface of a jaw of the holder to prevent accidental rotation of the same.

2. A pivotally mounted blade holder comprising upper and lower jaws between which the blade is placed from the front thereof, and locking and positioning means adapted to engage with side notches in the razor blade, which locking and positioning means
- 5 comprise a rotatably mounted notched pin extending between the jaws and adapted to be rotated to be moved out of and into engagement with a side notch in the blade, and thumb operated means attached to said pin
- 10 which engages with the surface of a jaw of the holder to prevent accidental rotation of the same.

3. A pivotally mounted blade holder comprising upper and lower jaws between which the blade is placed from the front thereof, and locking and positioning means arranged at each side of the holder and adapted to engage with side notches in the razor blade, which locking and positioning means
- 20 comprise rotatably mounted pins extending between the jaws and adapted to be rotated to be moved out of and into engagement with the side notches in the blade, and thumb operated means attached to said pins
- 25 which frictionally engage with the surface of a jaw of the holder to prevent accidental rotation of the same.

4. A pivotally mounted blade holder comprising upper and lower jaws formed of bent sheet metal between which jaws the blade is placed from the front thereof, and locking and positioning means arranged at each side of the holder and adapted to engage with side notches in the razor blade, which locking and positioning means comprise rotatably mounted pins extending between the jaws and adapted to be rotated to be moved out of and into engagement with the side notches in the blade, and thumb operated means attached to said pins which engage with the surface of a jaw of the holder to prevent accidental rotation of the same.

5. A rotatably mounted blade holder for safety razors comprising a hinge pin, upper and lower jaws formed by bending a sheet metal blank upon itself and around such hinge pin, and locking means, adapted to engage with side notches in the razor blade, comprising rotatably mounted pins on each side of the holder, said pins being notched and having levers for rotating the same which levers when in the locking position lie on the underside of the lower jaw.
